UNITED STATES PATENT OFFICE

92,935

DESIGN FOR A CHAIN SANDAL

Harry Stern, Brooklyn, N. Y., assignor to Ansonia Bootery, Inc., New York, N. Y., a corporation of New York

Application May 24, 1934, Serial No. 51,903

Term of patent 3½ years

To all whom it may concern:

Be it known that I, HARRY STERN, a citizen of the United States, residing in Brooklyn, New York, county of Kings, and State of New York, have invented a new, original, and ornamental Design for a Chain Sandal, of which the following is a specification, reference being had to the accompanying drawing, forming part thereof.

In the drawing:—

Figure 1 is a top plan view of a sandal showing the new design in which the upper is made of a plurality of lengths of chains, and

What is claimed is:

The ornamental design for a chain sandal, as shown and described.

HARRY STERN.
